MEANS FOR APPLYING A TRIMMING CONDENSER TO A MAIN CONDENSER

Emil Dudley Koepping, Haddon Heights, N. J., assignor to Radio Condenser Company, Camden, N. J.

Application May 7, 1931, Serial No. 535,592

7 Claims. (Cl. 175—41.5)

This invention relates to the construction of variable condensers used in radio receiving sets, although it may have other uses.

In my application, S. N. 469,033, filed July 19, 1930, I have shown and described a construction of a condenser which may be built up by the condenser manufacturer, tested or calibrated, and placed in stock ready for shipment against orders received by the radio set manufacturer. The 10 specifications of the different set manufacturers vary as to the characteristics of the condensers required in their respective tunable circuits—some desire what is referred to in the trade as a trimming condenser by which the initial minimum capacity of the condenser can be adjusted, while others do not require or ask for the tuning 15 condensers to be equipped with trimmers.

In certain designs of receiving sets, the space may be very limited, and consequently the design 20 of the tuning condenser must be very compact, and it is the principal object of my invention to provide a construction by which a trimming condenser may be applied to a condenser that has already been made, calibrated, and stocked, without changing or throwing out the calibration of 25 the main condenser by the addition of the trimmer.

Stated in another way, it is the object of my present invention to attain the advantages set 30 forth in my application herein identified, when applying the principles to a compact design of condenser. By way of illustration, but not of limitation, I have shown my improvement applied to a two-gang condenser, but it is to be understood that the invention may be applied to any number of units which may be arranged in 35 gang form for single control. Of course, the invention may be applied to a single unit condenser if so desired.

40 In the drawing:

Figure 1 illustrates a side elevation of a two-unit gang condenser with the rotor moved slightly out of its maximum capacity position, and showing the trimmer condenser removed from one of 45 the units.

Figure 2 is a view on the line 2—2 of Figure 1.

Figure 3 is a plan view of the special bracket for mounting the trimmer condenser.

Figure 4 is a section on the line 4—4 of Figure 3.

50 In the drawing, 1 is a frame having end support plates 2 and 3 which carry a shaft 4 supported by anti-friction bearing members carried in the races 5 and 6, substantially in the same manner as shown and described in Cramer Patent 1,800,719, issued April 14, 1931. On the shaft

4, are mounted in any satisfactory manner, a pair of sleeves 7 which support a plurality of rotor plates 8, the ends of which are preferably fastened together by tie bars 9. Each stator group of plates 10 is supported by tie bars 11 which are clamped, by means of the clamping bar 12 and screws 13, to one end of an insulator 14. The other end of the insulator 14 is fastened in any suitable manner as by rivets 16, to a lug 15 thrown upwardly from the side of the frame 1.

5 As shown in Figure 1, the insulators 14 are positioned in openings 17 which are punched in the frame 1 preferably at the time the lugs 15 are formed. It is to be understood that both sides of each of the stator units are fastened to the frame 15 1 in the manner just described.

In the construction shown, it is to be noted that the insulator 14 is relatively narrow and there is not room between the screws 13 and the rivets 16 to properly mount a trimming condenser 20 on the insulator 14. Besides, as has been pointed out, the screws 13 should not be disturbed after the stator has been fastened in its working position and the condenser has been calibrated to its rated capacity. Therefore, some special means 25 must be provided for mounting the trimming condenser on one or both sides of each of the condenser units.

In order to accomplish this, I have provided a bracket 18 having holes 19 therein through which 30 the screws 13 pass, thereby clamping the bracket 18 securely under the heads of the screws 13. The bracket therefore also serves as a washer for the heads of the screws 13. As will be noticed in Figures 2, 3 and 4, the bracket 18 is provided with 35 an offset and the lower portion thereof is provided with a pair of upturned side lugs 20, and between these side lugs, the extended part 21 of the trimmer plate 22 is positioned. These lugs prevent

40 the trimmer plate from turning or moving laterally when the screw 23, which is adapted to fit the tapped hole 24, is tightened to fasten the plate on the bracket. Also, when the screw 26 is moved to adjust the cap of the trimmer condenser, the movement of the screw tends to weave the plate 45 21 on the bracket, and the side lugs 20 prevent this weaving action and make possible a smooth adjustment of capacity. The trimmer condenser plate 22 overlaps the frame 1 and is kept from

50 contacting with the frame 1 by a suitable insulator 25, preferably of mica, which is held in position by two lugs 28 and an adjusting screw 26 that passes through a bushing 27 of insulating material.

The trimmer condenser 22, including its extension 21, is so formed that there is a spring tension always acting outwardly away from the frame 1, so that as the screw 26 is backed away from the plate 1, the trimmer plate 22 will follow the screw, and of course when the screw is turned inwardly the plate 22 is of course nearer the plate 1, thereby slightly changing the capacity of the main condenser unit, it being understood that the screws 13 which are fastened to the bracket 18 through the insulator 14, connect each stator group with the trimmer condenser plate 22.

The extension 21 of the plate 22 is provided with an orifice 29 to receive a conductor which is soldered to said extension, thereby completing a connection from the condenser to the trimmer plate, as well as the stator of the main condenser. When the trimmer plate 22 is not used, the conductor for the stator circuit may be connected directly to the bracket 18 by use of the screw 23 and suitable washers, or a small terminal may be used, one end being clamped to the bracket 18 by screw 23, while the conductor is soldered to its opposite end. If it is desired at a later time to add the trimmer plate, the conductor can be readily transferred from the bracket or terminal, as above set forth, to the plate after mounting it on the bracket.

Since the condenser is assembled with the bracket 18, which is a relatively inexpensive piece, when the condenser is originally assembled, it will be seen that the trimmer condenser 22 may be applied to the bracket 18 in the manner described without affecting the original setting of the main condenser, and consequently, its original calibration is not disturbed.

Having thus described my invention, what I claim is:

1. In an electrical condenser having a frame and relatively fixed and movable sets of elements carried thereby, one set being fastened to at least two insulators carried by the frame, a bracket permanently attached to at least one of the insulators by said one set fastening means, a trimmer condenser plate adapted to be mounted on said bracket, and means for adjusting the capacity position of said plate with respect to the frame.

2. A main condenser having a frame, stator and rotor groups of plates, said stator group of plates being held together by a plurality of means fastened to insulators carried by the frame, at least one of said insulators having a bracket fas-

tened thereto, a trimmer condenser plate having a part adapted to be fastened to said bracket and overlying a part of the frame, and means for adjusting the capacity position of said plate with respect to the frame.

3. Quick attachment means for applying a trimming condenser to a main condenser having its stator fastened to insulators supported on a frame, comprising a bracket held to one of said insulators by the stator fastening means, a plate 10 adapted to be mounted on the bracket so as to extend over a part of the frame, and means carried by the frame for adjusting the position of said plate with respect to the frame.

4. In a compact type of main condenser having a frame and fixed and movable groups of plates carried by the frame, said fixed groups of plates having mounting means fastened to one end of relatively narrow insulators attached to the frame at their opposite ends; means for applying a trimming condenser to the main condenser consisting of, a bracket held to at least one of the insulators by a part of said stator mounting means, a plate adapted to be fastened to the bracket and extending over a part of the frame, means for preventing the plate from coming into direct contact with the frame, and means for adjusting its position with respect to the frame.

5. In an electrical condenser as set forth in claim 1, further characterized in that the bracket has a pair of upturned side lugs between which a part of said condenser plate is positioned, whereby the plate is prevented from rotating or shifting laterally on the bracket.

6. A compact type of condenser as set forth in claim 4, further characterized in that the bracket is provided with means for preventing the trimmer condenser plate from shifting on the bracket when it is being fastened in position.

7. An electrical condenser having a frame, stator and rotor groups of plates carried by the frame, said stator group of plates being mounted on insulators fastened to the frame, a bracket carried by at least one of said insulators and electrically connected to the stator group of plates, a trimmer plate adapted to be fastened to the bracket and having a part extending over a part of the frame but out of contact therewith, and means for adjusting the capacity position of said trimmer plate with respect to the frame.

EMIL DUDLEY KOEPPING.
